UNITED STATES PATENT OFFICE

2,468,893

AIRPLANE AMUSEMENT DEVICE

Albert Orance, Chicago, Ill.

Application March 19, 1946, Serial No. 655,493

5 Claims. (Cl. 272—36)

1

This invention relates to improvements in amusement devices, and more particularly to miniature airplanes supported at the outer extremities of rotatably mounted hinged girders, whereby a limited amount of movement of the airplane may be had and controlled by the occupants thereof.

An object of the invention is to provide an improved airplane roundabout for circuses and carnivals, the same being portable, and highly thrilling.

Another object of the invention is to provide an improved amusement device including a pair of rotatably mounted hinged girders supporting miniature airplanes at their ends, said airplanes being capable of horizontal rocking movement with respect to said girders, and said movement being controllable by the occupants of the airplanes.

A still further object of the invention is to provide an improved airplane roundabout for circuses and carnivals, and the like, which will be highly exciting and thrilling to the occupants, and relatively inexpensive to manufacture and produce.

Other objects will appear as the description proceeds.

In the accompanying drawings which form a part of this application,

Figure 1 is a side elevation of the improved airplane amusement device;

Figure 2 is a plan view of the airplane amusement device;

Figure 3 is a sectional view taken on the line 1—3 of Figure 2;

Figure 4 is a sectional view taken on the line 4—4 of Figure 3;

Figure 5 is a sectional view taken on the line 5—5 of Figure 3, and

Figure 6 is a sectional view taken on the line 6—6 of Figure 1.

Like characters of reference are used throughout the following specification and the accompanying drawings to designate corresponding parts.

In carrying out the invention, there is provided a heavy circular ring base or supporting platform 1, which supports the centrally disposed upstanding cylindrical housing 2, the same being preferably formed integrally with said base. Upwardly converging bars 50 interconnect the ring base and the housing to additionally brace the latter. The housing 2 is also provided with the four vertically extending guide slots 3 ar-

2

ranged equidistant from each other and extending through the wall of said housing.

The cross-head 4 provided with four radially extending arms 5 is arranged to have said arms extend through the guide slots 3 in the cylindrical housing 2, for vertical movement therein. A hydraulic jack 6 is supported within the lower extremity of the housing 2, and is provided with the piston 7 and interconnecting piston rod 8, said rod being reduced as at 9 to extend through and form a shoulder engageable with the lower surface of the cross-head 4, as clearly shown in Figure 3 of the drawings.

A ball bearing ring 10 is positioned about the housing 2 in contact with the upper surface of the cross-head 4, and in turn supports the rotatable cylindrical housing 11 which is of a diameter to snugly fit the housing 2. A gear 12 is formed integrally about the lower end of the housing 11, and meshes with the elongated driving gear 13 supported on the vertically extending shaft 14 mounted in the spaced bearing brackets 15 and 16. A gear 17 is mounted on the lower end of the shaft 14 and intermeshes 25 with the worm gear 18 in the gear housing 19, the same being connected to the shafts of the driving electric motor 20, supported on the base 1.

A supporting ring or collar 21 will be formed integrally with the housing 11, and includes the radial arms 22 and the bracing rods or bars 23 connected between said housing 11 and the ring 21 adjacent its outer extremities.

The annular collar 24 is formed integrally on the housing 2 adjacent its upper end, and supports the annular ball bearing race 25. Disposed about the upper end of the housing 11, and rotatably mounted on said housing and ball bearing race, is a girder supporting collar 26 having an enlarged supporting flange 27, having hinges 28 attached thereto at opposite points to connect with the inner ends of the girder frame arms 29. Webs 30 will be formed between the collar 26 and the flange 27 to strengthen the construction. A lock nut 31 will be secured to the top of the housing 2 to retain all of the parts in position thereon.

Heavy coil springs 32 will be positioned between the girder arms 29 and the supporting flange 27, by means of the cap members 33 pivoted to the ears 34 on the girder arms 29 and the base member 35 on the ring 21, it being understood that the opposite ends of the springs 32 are positively secured to the members 33 and 35.

Secured to the outer ends of the girder arms

29, are the miniature airplane supporting rods 36, which are adapted to extend through the body or fuselage of the airplanes 37, to normally hold them in substantially horizontal position with respect to the ground when the apparatus is not in operation.

Secured to each miniature airplane and extending inwardly from the body of the same, are the spaced movement limiting bars 39 and 40 which cooperate with the triangular shaped arms 41 fixed to the supporting rods 36. Extensions 52 are provided at the sides of the arms 41 to engage the stop bars 39 and 40 when the airplane bodies have tilted forwardly or backwardly to their extreme limit of movement. The arms 41 will also engage said stop bars 39 and 40 to provide a second means for limiting the movement of the airplane bodies.

The elevators 42 will be operable by the persons sitting in the airplane, the same being connected with a control stick (not shown). Hence, if properly controlled, the occupants will be able to manipulate the airplanes so that they will tilt forwardly or backwardly as they are rotated with the girders 29 at a high rate of speed.

The mode of operation of the apparatus will be now described:

Assuming the occupants or patrons are in each miniature airplane, the operator of the device or roundabout sees that the occupants are strapped in by means of safety belts, after which he starts the electric motor 20, and admits fluid under the piston 7 of the hydraulic jack 6, to elevate the collar supporting ring 21 to which the girder arms 29 are connected through the heavy coil springs 32, which action elevates the outer ends of the girder a considerable distance from the ground as shown in dotted lines in Figure 1. The occupants may control the elevators of the airplanes and get the effect of "taking off," and when the apparatus is being stopped, the proper use of the elevators control will cause a good "three point" landing on the wheels and tail skid of the airplanes. If the occupants fail to control the elevators properly, the airplane will merely "buck" or tilt within the limits of their movements, in any event, the uncontrolled movements will never be severe enough to permit any injury to the occupants.

It will be noted that the springs 32 serve the purpose of drivingly interconnecting the girders 29 with the arms 22 which are in turn driven by the motor 20 and associated gearing 12 and 13. The springs 32 also act as shock absorbers retarding both the upward and downward movements of the girders 29. Thus when the operator releases the fluid in the hydraulic jack as he turns off the motor 20, the girders descend, the springs 32 acting to retard this downward movement and allow the device to come to a smooth and easy stop.

While the preferred embodiment of the invention has been illustrated and described, it will be understood that it is not intended to limit the scope of the invention thereto, as many minor changes in the field of construction may be resorted to without departure from the spirit of the invention.

Having thus described my invention, what I claim as new and desire to secure by Letters Patent of the United States is:

1. An airplane amusement device including a base having an upstanding cylindrical support thereon, a collar formed with a peripheral flange on its lower end rotatably mounted on the upper end of said support, a plurality of girders hinged

at their inner ends to said peripheral flange, airplanes supported on the outer ends of said girders, a vertically adjustable collar rotatably mounted on said cylindrical support in spaced relation below said first-mentioned collar being movable toward and away from the same and formed with a concentric supporting ring tied to said collar by means of radial arms and bracing rods, coil springs seated on said ring with their upper ends positively attached to said girders for resiliently supporting the same and for providing the driving connection between said lower collar and said girders, a gear formed about the lower end of said lower collar, an elongated driving gear intermeshed therewith, means for rotating said driving gear, and means for raising and lowering said lower collar and ring to raise and lower said connected girders for elevating and lowering the airplanes with respect to the ground as the airplane amusement device is operated.

2. An airplane amusement device including a base having an upstanding cylindrical support thereon, a collar formed with a peripheral flange on its lower end rotatably mounted on the upper end of said support, a plurality of girders hinged at their inner ends to said peripheral flange, airplanes supported on the outer ends of said girders, a vertically adjustable collar rotatably mounted on said cylindrical support in spaced relation below said first-mentioned collar being movable toward and away from the same and formed with a concentric supporting ring tied to said collar by means of radial arms and bracing rods, coil springs seated on said ring with their upper ends positively attached to said girders for resiliently supporting the same and for providing the sole driving connection between said lower collar and said girders, a gear formed about the lower end of said lower collar, an elongated driving gear intermeshed therewith, means for rotating said driving gear, and a hydraulic jack for raising and lowering said lower collar and ring to raise and lower said connected girders for elevating and lowering the airplane with respect to the ground as the airplane amusement device is operated.

3. The subject matter as claimed in claim 2, and means for limiting the vertical movement of said lower collar.

4. The subject matter as claimed in claim 2, means for limiting the vertical movement of said lower collar, and said hydraulic jack including a piston rod and a cross support on the upper end thereof upon which said lower collar will be supported for vertical movement.

5. The subject matter as claimed in claim 2, means for limiting the vertical movement of said lower collar, a hydraulic jack including a piston rod and a cross support on the upper end thereof upon which said lower collar will be supported for vertical movement, and means for controlling the movement of said airplanes at the outer ends of said girders.

ALBERT ORANCE.
